[57] CLAIM

The ornamental design for a “electrooptic timepiece face,” as shown and described.

DESCRIPTION

FIG. 1 is a front elevational view of an electrooptic timepiece face showing our new design in a non-energized condition;

FIG. 2 is a front elevational view thereof in the energized condition showing a representative time indication of 12:05.

The timepiece face is flat and of no appreciable thickness.

FIG. 1

FIG. 2

UNITED STATES PATENT AND TRADEMARK OFFICE
CERTIFICATE OF CORRECTION

PATENT NO. : DES. 243,076

DATED : January 18, 1977

INVENTOR(S) : H.B. THOMPSON, M.B. SHEFFIELD, R.J. GROHOSKI

It is certified that error appears in the above-identified patent and that said Letters Patent are hereby corrected as shown below:

UNDER DESCRIPTION, Fig. 2, CHANGE REPRESENTATIVE TIME
INDICATION FROM "12:05" to "12:08"

Signed and Sealed this
Thirty-first Day of May 1977
